UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

STEAM-HEATING APPARATUS.

1,264,786.

Specification of Letters Patent. Patented Apr. 30, 1918.

Application filed August 22, 1916. Serial No. 116,222.

To all whom it may concern:

Be it known that I, EDWARD E. GOLD, a citizen of the United States of America, residing in the borough of Manhattan, city, 5 county, and State of New York, have invented certain new and useful Improvements in Steam-Heating Apparatus, of which the following is a specification.

In my patent for an improvement in a thermostatic mechanism, No. 1,077,224, I have described a steam heating system for railway cars of the interchangeable type, that is to say, which may be arranged to work automatically as a pressure system admitting 15 steam to the radiators at the pressure of the train pipe or other source of steam under pressure, or as a vapor system having the steam in the radiators at approximately atmospheric pressure. In my Patent No. 20 1,087,164, I have illustrated an apparatus for use in a steam heating system accomplishing the same result. The present application is an improvement in a thermostatic controlling or regulating apparatus 25 for use in an interchangeable heating system.

The present invention involves the use of a thermostat which is exposed to the temperature of the discharge from the steam heating system and is movable in position so as to control either an inlet valve, whereupon the system will operate as a vapor system at substantially atmospheric pressure; or, in its other adjustment, will operate to 35 control an outlet valve so that the system shall operate as a pressure system, and, in an intermediate position, will enable both of the valves to be opened so as to operate as a blow-off.

40 This invention is applicable to direct or indirect radiating systems, and the term "radiator" is applied to the steam pipes whether their heat is radiated directly into the atmosphere to be warmed or through 45 the intermediation of a body of water. The admission and exhaust valves may be normally either open or shut and may assume their normal positions under the influence of steam pressure or a spring or weight.

50 In the accompanying drawings I have

illustrated the most desirable form of constructing my invention now known to me.

In the said drawings,—

Figure 1 is a perspective view of the principal parts of the system applied to the heating of railway cars; 55

Fig. 2 is a horizontal section through the thermostatic device and adjacent parts, the system being adjusted in full lines as a vapor system and showing in dotted lines, the adjustment as a pressure system; 60

Fig. 3 is a similar view, the system being adjusted as a blow-off;

Fig. 4 is a plan view of an adjusting handle set in the floor of the car; 65

Fig. 5 is a side view of the thermostatic apparatus the cover of the casing being removed;

Fig. 6 is a detail view of part of the thermostatic casing illustrating the means for 70 shifting the same.

My invention is illustrated in connection with a railway steam heating system having a train pipe A which carries the supply of steam to the various cars. This is provided beneath the floor B of each car with a pair of branches C, one running to each side of the car and each connected by a vertical branch D passing through the floor of the car and a horizontal branch E with 75 the radiator F. The hand-operated stop valve G is arranged within the car for use when the supply of steam is to be cut off entirely from the radiator.

In the horizontal branch C below the floor 85 of the car is an automatic admission valve indicated as a whole by the letter H. The discharged steam and water of condensation are led from the radiator through the inclined branch K within the car, the vertical 90 branch L passing through the floor of the car and the inclined branch M beneath the car.

A thermostat J is located in a position to be exposed to the temperature of the discharged steam or water of condensation from the radiator. This thermostat is preferably located within a casing N, into which pass the discharged steam and water of condensation from the radiator. This thermo- 100

stat is illustrated as a cell or so-called dia-
phragm, which is usually constructed of
spring metal, such as phosphor bronze, and
contains a small quantity of a volatile fluid,
such as ethyl chlorid, and which is caused
to expand as the temperature of the dis-
charge increases, and contract as the said
temperature is reduced. This thermostat is
mounted within the casing so as to be moved
10 to operative position relative to the inlet
or the outlet. In each position the thermo-
stat closes the respective valve. When the
temperature of the discharge rises sufficiently
15 high so that, if the thermostat is adjusted
to the full line position of Fig. 2 and the
temperature of the discharge from the radi-
ator is sufficiently great, the thermostat is
caused to expand, thereby closing the inlet
20 valve by pressing the valve disk O to its
seat and shutting off the supply of steam.
The outlet of the pipe M being then open,
the system will act in the well-known man-
ner of a vapor system, by admitting just
25 sufficient steam to maintain the temperature
within the pipes at substantially 212°.
If the thermostat J is adjusted to the
dotted line position of Fig. 2, the inlet valve
O will open under the influence of the spring
30 P and allow free flow of steam at train pipe
pressure, or such pressure as may be desired,
to the radiator. When the discharge from
the radiator is hot enough, the outlet valve
35 Q will be closed, thereby building up pres-
sure in the radiator until the temperature
within the casing falls to a point where the
thermostatic diaphragm J is contracted,
when it will open the outlet from the pipe
40 M and permit the discharge of the water of
condensation.
The discharge valve Q may be supported
in any suitable manner relative to the outlet
so as to be held open when it is not closed
45 by the thermostat. As illustrated, this valve
is movable with the thermostat, but this is
not essential.

When it is desired that both the inlet and
outlet valves should be open to permit blow-
ing-off of the pipes, the thermostat is capable
of adjustment to the position illustrated in
50 Fig. 3, where both the inlet and outlet valves
are open and steam may freely pass through
the pipes and blow the condensed water out
of the same.

The thermostat is illustrated as being
55 mounted in a carrier or cage R, wherein it is
held by short arms r (Fig. 5), permitting the
cage to be open at each side so that the
thermostat will be freely exposed to the
temperature of the discharge from the radi-
60 tor. The thermostat is suitably mounted
in the casing N so as to be capable of being
turned therein. As illustrated, such mount-
ing is by means of a pivot S upon which the
thermostat is journaled and which is suitably

supported in the casing. Desirable means 65
for shifting the thermostat, as illustrated,
comprise a stem T which projects up through
the floor of the car and there carries an in-
dicating handle t which indicates upon a dial
U whether the thermostat is adjusted to 70
"Vapor," "Blow-off," or "Pressure." At the
lower end of the stem T is a lever V which
has a pin and slot connection v v¹ with the
cage for turning the same.

It will be perceived that the illustrated 75
means for shifting the thermostat provide a
lock for holding the same in adjusted posi-
tion. This may be seen by an examination
of Fig. 2, wherein the thermostat is illus-
trated in full lines as being adjusted to con-
80 trol the inlet valve. The reaction of the
thermostat is exerted through the cage in
a straight line through the slot, pin and lever
V to the stem T, and this same result is ac-
complished when the thermostat is adjusted 85
to control the discharge valve, as illustrated
in dotted lines in said figure.

The inlet valve, which as a whole is design-
ated H, has a valve disk O carried by a
stem o and normally held open by a spring 90
P. The manner of operating the inlet valve
illustrated is by means of an abutment X
which is carried by the cage R and is mov-
able therein to permit the opening of the
95 valve as the thermostat contracts under the
influence of the spring P.

The valve disk O is provided with a seat
h which is illustrated as removable upon the
removal of the screw cap Y.

The casing N has a movable cover Z, 100
which is illustrated as being removed in Fig.
5. Locking means are provided for holding
this cover in place.

The casing N has a discharge or drip pipe
N¹ through which the discharge from the 105
radiator may escape to the atmosphere.
This drip pipe may be provided with a par-
tition or baffle plate N², as illustrated in my
Patent No. 1,007,862, for the purpose of
ventilating the casing and rendering the 110
thermostat more energetic.

The discharge valve Q is illustrated as be-
ing carried by the cage R, and by this
method of construction, it achieves the dou-
ble advantage of acting as a fixed abutment 115
to receive the thrust of the thermo-stat when
adjusted in position to operate the inlet
valve, as well as serving to close the dis-
charge opening. When it is adjusted to the
position to close the discharge opening, it is 120
normally held off of its seat by a spring Q¹
and, when closed, it is pressed against a
valve seat Q². A plug Z¹ is movably secured
in the casing in a position opposite the dis-
charge opening and enables the seat Q² to be 125
renewed, if desired.

Both the abutments Q and X have a suffi-
cient amount of play in the cage to enable

them to give to open their respective valves as the thermostat contracts, and both are provided with flanges engaging against shoulders in the cage which prevent their 5 passing out of the cage and enable them to act as abutments in the respective operative positions of the thermostat.

The cage R is provided with a suitable number of arms r to hold the thermostat in 10 place. Four of such arms are illustrated at each side and at the inner ends of these arms the abutments Q, X are carried. The stem T is provided with two arms V which are held on squared portions of the stem, as 15 illustrated in Fig. 3, and these arms engage opposite sides of the cage, as illustrated in Fig. 6, for the purpose of adjusting the same in position.

When the system has been operated under 20 pressure and the heat is cut off by the stop valve, condensation of the steam in the pipes causes a vacuum, which draws up or holds up water in the pipe to a certain extent and introduces a liability to freezing. To prevent 25 this, I prefer to use a gravity operated trap of the style shown in my Patent No. 522,253. The arrangement of such a trap is shown in Fig. 2, where the trap is lettered generally G¹. Its operation is fully described 30 in my Patent No. 1,087,164 and need not here be repeated. If desired, this apparatus might be converted into a simple vapor system or into a simple pressure system, by means such as are illustrated or described 35 in my Patent No. 1,087,164 with reference to the system there shown.

In the operation of my improved device, let it be assumed that the system is desired to act as a vapor system, in which case the 40 stem T, by means of the handle t, will be turned so that the indicator will point as illustrated in Fig. 4, whereupon the cage and thermostat will be in the position of Fig. 2. The inlet valve O, however, will be held open by the spring P permitting the 45 steam freely to enter the radiator. When the radiating pipes have become sufficiently warm the temperature of the discharge from the pipe M expands the liquid in the thermostatic vessel J and causes the said vessel to swell up, which will press the abutment Q to its seat in the cage, whereupon the 50 said abutment will serve as a reaction element transmitting the thrust of the thermostat through the cage and arm V to the stem T and so to the casing and thereupon will exert pressure against the abutment X and cause the same to close the inlet valve O. This valve will remain closed until the 55 temperature of the discharge from the pipes causes the temperature within the casing N to drop to a point where the thermostat contracts. Thereupon the spring P will open the valve O and the foregoing op-

eration will be repeated. If it now be desired to secure a greater supply of heat from the radiating pipes, the handle t may be turned to "Pressure" and this will give the stem T a quarter turn and shift the cage and thermostat to the position illustrated 70 in dotted lines in Fig. 2. Thereupon, when the temperature of the escaping steam has heated the thermostat sufficiently to expand the same, it will press the abutment X to its seat in the cage, which will then serve as a 75 reaction element whereby the pressure of the thermostat is transmitted through the pin and slot v v¹ to the stem T and so to the casing. The continued expansion of the thermostat will press the abutment Q toward 80 the seat Q², compressing the spring Q¹, until the same completely closes the outlet from the radiator. It will remain in this position until the temperature within the casing, under the influence of the ventilating plate N² 85 has dropped sufficiently to contract the thermostat, whereupon the spring Q¹ will cause the valve Q to open, releasing the water of condensation from the radiator and connected pipes. 90

When it is desired to blow steam through the pipes, the handle may be turned to the position of "Blow-off" in Fig. 4, whereupon the cage will be in the position indicated in Fig. 3 and the inlet valve O will be opened 95 by the spring P and likewise the outlet valve will then be opened and steam may freely circulate through the pipes.

I have illustrated and described the most desirable manner of constructing my invention now known to me, but modifications may be made therein and changes in the construction within the skill of a mechanic and the limits of the appended claims. 100

What I claim is:—

1. A regulator for a steam heating system comprising inlet and outlet valves, and a thermostat heated by the discharge and mounted to swing to different angular positions, in one of which it is in operative control of the inlet valve and in the other of which it is in operative control of the outlet valve. 105

2. The regulator of claim 1 having a pivoted cage carrying the thermostat. 110

3. The regulator of claim 1 having operative means for swinging the thermostat adapted in each operative position of the thermostat to lock it there against the reactive pressure. 115

4. The regulator of claims 1 and 2 having operative means for moving the cage adapted in each operative position of the thermostat to lock it there against the reactive pressure. 120

5. The regulator of claim 1 having means for moving the thermostat to either of said positions adapted to hold it in an interme-

diate position in which it controls neither valve and permits free blow off of steam.

6. The regulator of claims 1 and 2 having the cage pivoted to swing from either 5 operative position to the other.

7. The regulator of claims 1 and 2 having the cage pivoted to swing from either operative position to the other, and having an operating stem carrying an arm engaging 10 the cage to swing it.

8. In the regulator of claims 1 and 7, the arm arranged to aline with the reactive pressure in either operative position to lock the cage.

15 9. The regulator of claims 1 and 8, the arm having a pin and slot connection with the cage.

10. In the regulator of claims 1 and 9, the cage having a slot and the arm having 20 a pin, and the arm movable in either final position to bring it perpendicular to the slot.

11. A steam heating system including in combination radiating pipes, an admission 25 valve, a chamber into which said radiating pipes discharge, a cage pivotally mounted in said chamber, an expansible thermostatic vessel loosely carried by said cage and exposed to the temperature of the discharge from said radiating pipes, movable abutments carried by said cage and disposed on 30 opposite sides of said thermostat, one of said abutments in one position of said cage acting to close the outlet from said radiator and the other abutment acting in another 35 position of the cage to operate the admission valve, both of said operations controlled by said thermostat and in each position the other abutment acting as a stop for the thermostat.

40 12. A steam heating system including in combination radiating pipes, an admission valve, a chamber into which said radiating pipes discharge, a cage pivotally mounted in said chamber, an expansible thermostatic 45 vessel loosely carried by said cage and exposed to the temperature of the discharge from said radiating pipes, movable abutments carried by said cage and disposed on opposite sides of said thermostat, one of said abutments in one position of said cage acting 50 to close the outlet from said radiator and the other abutment acting in another position of the cage to operate the admission valve, both of said operations controlled by said thermostat and in each position the 55 other abutment acting as a stop for the thermostat, and in an intermediate position of said cage both said valves being withdrawn from their seats.

60 13. A regulator for a steam heating system, comprising a casing having at its sides means for connection to steam supply and discharge pipes respectively, a cage pivotally mounted in said casing, means for turn-

ing said cage, and a thermostat carried by 65 said cage and adapted as the same is turned to be brought into operative relation to close said steam supply and discharge pipes respectively.

14. A regulator for a steam heating system, comprising a casing having at its sides means for connection to steam supply and discharge pipes respectively, a cage pivotally mounted in said casing, means for turning 70 said cage, a thermostat carried by said cage and adapted as the same is turned to be brought into operative relation to said steam supply and discharge pipes respectively, and a movable abutment carried by said cage on each side of said thermostat, said 75 abutments adapted respectively alternately to control the supply and discharge pipes under the influence of said thermostat and to serve as abutments for said thermostat.

15. A regulator for a steam heating system, comprising a casing having at its sides means for connection to steam supply and discharge pipes respectively, a cage pivotally mounted in said casing, means for turning 80 said cage, a thermostat carried by said cage and adapted as the same is turned to be brought into operative relation to close 85 said steam supply and discharge pipes respectively, and an open outlet from said casing.

16. A regulator for a steam heating system, comprising a casing having at its sides means for connection to steam supply and discharge pipes respectively, a cage pivotally mounted in said casing, means for turning 90 said cage, a thermostat carried by said cage and adapted as the same is turned to be brought into operative relation to said steam supply and discharge pipes respectively, and a movable abutment carried by said cage 95 on each side of said thermostat, said abutments adapted respectively alternately to control the supply and discharge pipes under the influence of said thermostat and to serve as abutments for said thermostat, and a gravity trap in said casing.

17. A regulator for a steam heating system, comprising a casing, having at its sides, means for connection to steam supply and discharge pipes respectively, a cage pivotally mounted between said respective means, a lever having a slotted connection with 115 said cage and a handle for turning the same, and a thermostat carried by said cage and adapted as the same is turned to be brought into operative relation to close said steam supply and discharge pipes respectively.

18. A steam heating system including in combination radiating pipes, an admission valve, a chamber into which said radiating pipes discharge, a cage pivotally mounted in 120 said chamber, an expansible thermostatic 125

vessel loosely carried by said cage and exposed to the temperature of the discharge from said radiating pipes, movable abutments carried by said cage and disposed on opposite sides of said thermostat, one of said abutments in one position of said cage acting to close the outlet from said radiator and the other abutment acting in another position of the cage to operate the admission valve, both of said operations controlled by said thermostat and in each position the other abutment acting as a stop for the thermostat, and means for turning said cage, comprising a lever having a pin and slot connection therewith and a handle in the car for turning said lever.

19. A steam heating system for railway cars, including in combination radiating pipes, an admission valve, a discharge valve, a chamber located below the car floor, and a thermostat exposed to the temperature of the discharge from said radiating pipes, and movable in position and adapted, according to position, to operate one or the other of said valves, and means for supporting and moving said thermostat, comprising a cage

pivottally mounted in said chamber and a lever mounted to turn therein, and having at its free end a sliding connection with said cage, and a handle for turning said lever in the car, said lever adapted to lock the cage in adjusted position.

20. A regulator for a steam heating system comprising a thermostat and valve abutments, and a swinging cage having seats for said abutments and loosely confining the thermostat between them.

21. A regulator for a steam heating system comprising a thermostat and a swinging cage therefor, and opposite abutments movably seated in the cage, and either one serving to receive the reaction of the intervening thermostat while the other transmits the operative movement of the thermostat.

In witness whereof, I have hereunto signed my name in the presence of two subscribing witnesses.

EDWARD E. GOLD.
